UNITED STATES PATENT OFFICE.

ROBERT FINKELSTEIN, OF BROOKLYN, NEW YORK, ASSIGNOR TO HERSCHEBERG & COMPANY, OF NEW YORK, N. Y., A CORPORATION OF NEW YORK.

HAT.

Application filed April 2, 1925. Serial No. 20,027.

To all whom it may concern:

Be it known that I, ROBERT FINKELSTEIN, a citizen of the United States, residing at Brooklyn, in the county of Kings and State of New York, have invented certain new and useful Improvements in Hats, of which the following is a specification.

My present invention relates to hats, particularly of a type adapted for children, in which portions of the hat will extend down over at least a portion of the ears of the wearer and, at the same time, will fit the head of the wearer without pressure on the ears.

15 My invention will be best understood from the annexed drawing and the following description of an illustrative embodiment of my invention, in which Fig. 1 is a side view of an illustrative embodiment and Fig. 2 is a cross-section of Fig. 1 looking from the right of Fig. 1.

Like reference characters indicate like parts throughout the drawing.

20 In the drawings, the crown 10 is made up of sections with their edges sewed together in the usual manner, but instead of the lower edge of the crown being horizontal when the crown is positioned as shown in the drawing, this lower edge is higher at the sides of the crown than at the front and back. That is to say, there is a cut-off or recess at 101 just above the position of the ears of the wearer so that the lower edge of the crown is higher at that point than at the front 25 or the back 103.

25 The hat is usually provided with a sweat band 17 which will be shaped to conform to the lower edge of the crown, so that it also will have a portion above the ears of the wearer higher than at the front and back of the hat. Preferably the lower edge of the sweat band will substantially parallel the lower edge of the crown.

30 The hat illustrated is provided with a brim 11 which extends below the lower edges of the crown and, in the arrangement shown in the drawing, this brim is made up of a piece of material folded at 14 to provide the two layers 12 and 13 and with a filling piece 16 between the two layers, if desired. The edges of this folded piece are turned inwardly and downwardly against the sides of the lower part of the crown 10 and sewed thereto by a line of stitches 15 which preferably extend horizontally around the hat at a

point above the highest part of the recess 101. Preferably, also, I make the brim 11 so that its lowermost edge at the sides of the hat is farther from the top of the crown than is such lower edge at the front and back of the hat.

35 Preferably I make the hat as follows:

The crown is first made in the usual manner with its lower edge horizontal. Then the brim 11 with its lower part turned up, is sewed to the crown by the line of stitches 15. Then the operator cuts out the recess 101, the line of stitches 15 having been located so that this could be done without interfering with the stitching. Then the raw edges of the crown and brim where they are joined, may be covered by any appropriate binder and the sweat band 17 placed in the hat.

40 It will be noted that in the hat as described, the hat will fit around the head of the wearer but without pressing against the ears of the wearer because of the recess 101 provided for that purpose. The brim 11, in the form illustrated, extends down over the ears of the wearer but without pressing them and the ears are thus covered while, at the same time, the hat fits the wearer's head perfectly and without pressure on the ears. By extending the middle portion of the brim lower than at the front and back, as shown, a further advantage is obtained in that the ears of the wearer are covered more completely without extending the brim unduly below the crown at the front and back of the hat.

45 It will be understood that the arrangement which I have shown is merely illustrative and that the embodiment of my invention may be widely varied. Thus while I have shown the brim of the particular shape, it will be understood that this shape is not essential. It may, for instance, be made circular in cross-section or any other desired shape.

50 In the appended claims, I have used the terms "horizontal" and "vertical" in a relative sense only and as terms to describe my improved hat when it is held in the ordinary position of wear or in the position shown in the appended drawings.

I claim:

55 1. A hat having a crown with its lower portion substantially vertical and its lower edge generally horizontal with a cut-out at each side of the crown above the position of

100

- the wearer's ears, and a brim connected to the lower edge of the crown and extending outwardly and downwardly below the lower edge of the crown.
5. 2. A hat having a crown with its lower portion substantially vertical and its lower edge generally horizontal with a cut-out at each side of the crown above the position of the wearer's ears, and a brim connected to the lower edge of the crown and extending outwardly and downwardly below the lower edge of the crown, the lower edge of the brim at the sides of the hat being farther below the top of the crown than at the front and back of the hat.
10. 3. A hat having a crown with its lower portion substantially vertical and its lower edge generally horizontal with a cut-out at each side of the crown above the position of the wearer's ears, and a brim attached to the lower edge of the crown and extending upwardly for a short distance in contact with the exterior of the crown and then outwardly and downwardly with its lower edge below the level of the lower edge of the crown, 30 the lower edge of the brim at the sides of the hat being farther below the top of the crown than at the front and back of the hat.
15. 4. A hat having a crown with its lower portion substantially vertical and its lower edge generally horizontal with a cut-out at each side of the crown above the position of the wearer's ears, a brim extending upwardly for a short distance in contact with the exterior of the crown and then outwardly 40 and downwardly with its lower edge below the level of the lower edge of the crown, and a substantially horizontal line of stitches through said upwardly extending portion of the brim and the lower portion of the crown 45 on a level above said cut-outs.

ROBERT FINKELSTEIN.

the wearer's ears, and a brim connected to the lower edge of the crown and extending outwardly and downwardly below the lower edge of the crown.

5. 2. A hat having a crown with its lower portion substantially vertical and its lower edge generally horizontal with a cut-out at each side of the crown above the position of the wearer's ears, and a brim connected to

10 the lower edge of the crown and extending outwardly and downwardly below the lower edge of the crown, the lower edge of the brim at the sides of the hat being farther below the top of the crown than at the front and back of the hat.

3. A hat having a crown with its lower portion substantially vertical and its lower edge generally horizontal with a cut-out at each side of the crown above the position of

20 the wearer's ears, and a brim attached to the lower edge of the crown and extending upwardly for a short distance in contact with the exterior of the crown and then outwardly and downwardly with its lower edge below

25 the level of the lower edge of the crown.

26. 4. A hat having a crown with its lower

portion substantially vertical and its lower edge generally horizontal with a cut-out at each side of the crown above the position of the wearer's ears, and a brim attached to the 30 lower edge of the crown and extending upwardly for a short distance in contact with the exterior of the crown and then outwardly and downwardly with its lower edge below the level of the lower edge of the crown, 35 the lower edge of the brim at the sides of the hat being farther below the top of the crown than at the front and back of the hat.

5. A hat having a crown with its lower portion substantially vertical and its lower edge generally horizontal with a cut-out at each side of the crown above the position of the wearer's ears, a brim extending upwardly for a short distance in contact with the exterior of the crown and then outwardly 45 and downwardly with its lower edge below the level of the lower edge of the crown, and a substantially horizontal line of stitches through said upwardly extending portion of the brim and the lower portion of the crown 50 on a level above said cut-outs.

ROBERT FINKELSTEIN.

Certificate of Correction.

It is hereby certified that the name of the assignee in Letters Patent No. 1,566,663, granted December 22, 1925, upon the application of Robert Finkelstein, of Brooklyn, New York, for an improvement in "Hats," was erroneously written and printed as "Herschberg & Company," whereas said name should have been written and printed as *Hirschberg & Company*, as shown by the records of assignments in this office; and that the said Letters Patent should be read with this correction therein that the same may conform to the record of the case in the Patent Office.

Signed and sealed this 19th day of January, A. D. 1926.
